DESIGN FOR A HANDBAG OR SIMILAR ARTICLE

John C. Marks, New York, N. Y.

Application January 14, 1944, Serial No. 112,234

Term of patent 3½ years

To all whom it may concern:

Be it known that I, John C. Marks, a citizen of the United States of America, residing in the city of New York, county of New York, and State of New York, have invented a new, original, and ornamental Design for a Handbag or Similar Article, of which the following is a specification, reference being had to the accompanying drawing, forming part thereof.

The figure is a front perspective view of a handbag or similar article showing my new design.

The opposite side of the handbag or similar article is substantially the same as the side shown, and described.

I claim:

The ornamental design for a handbag or similar article, substantially as shown.

JOHN C. MARKS.
